Harold A. Roselund.

By *Own & Own.*

Attorney.

UNITED STATES PATENT OFFICE

HAROLD A. ROSELUND, OF TOLEDO, OHIO, ASSIGNOR TO THE DE VILBISS COMPANY, OF TOLEDO, OHIO, A CORPORATION OF OHIO

LIQUID GUN

Application filed March 19, 1932. Serial No. 599,898.

This invention relates to liquid-ejecting means, and particularly to those of the gun-type, and has for its object the provision of a simple, efficient and improved device of this character, which is particularly adapted for and provides a convenient and economical means of applying penetrating or other lubricating liquids in a fine stream and with considerable force to springs, shackles, body connections, seams, and other points of automobiles requiring lubrication.

The invention is fully described in the following specification, and an improved embodiment thereof is illustrated in the accompanying drawing, in which—

Figure 1 is a side elevation of a device embodying the invention, with parts broken away. Fig. 2 is an enlarged longitudinal sectional detail of the nozzle portion of the device, and Fig. 3 is an enlarged section on the line 3—3 in Fig. 1.

Referring to the drawing, 1 designates a receptacle for containing the liquid to be applied, the top of which receptacle is provided with an open neck 2 to which the lower end of a head member or handle 3 is threaded, or otherwise suitably attached, to permit easy separation thereof. The member 3 is vertically elongated and fashioned to adapt it to form a handle to be grasped by the hand of the operator, and is hollow to provide a space 4 therein from its lower end to near its top.

A bore 5 is provided in the upper end of the head 3 in angular relation to its vertical or longitudinal axis, and projecting from the outer end of this bore is a discharge tube 6 which terminates at its outer end in a nozzle 7 having a fine discharge orifice 8 therein, preferably spaced from the outer end of the nozzle by a cavity 9.

A liquid supply tube 10 extends from the inner end of the bore 5 down through the space 4 and into the receptacle 1 where it connects with a pump body 11 and communicates with the bottom portion of the cylinder 12 thereof through a passage 13. The cylinder 12 has an inlet passage 14 in its bottom in communication with the interior of the receptacle 1, and this passage is normally closed by an inwardly opening check-valve 15, while

the passage 13 is normally closed by an outwardly opening check-valve 16.

The tube 10 is held centered in the lower end portion of the head space 4 by a disc 17, which is held seated against a shoulder 55 in the head member 3 by a gasket 18, which in turn seats on the upper end of the receptacle neck 2 when the head member is mounted thereon. The lower end of the tube 10 carries the pump body 11 so that the latter is removed with the tube 10 from the receptacle when the head member is disconnected therefrom. The disc 17, in addition to centering the liquid tube 10, also serves to prevent oil from entering the hollow head 3 in case the 60 gun is upset.

A plunger 19 is mounted in the pump cylinder 12 and has an operating stem 20 extending upward therefrom through the disc 17 and to near the upper end of the head space 70 4 where it is engaged by an operating lever 21. This lever, in the present instance, is of U or forked-form, being fulcrumed, in the present instance, near its closed end on a pin 22 in the upper end of the space 4, and has its legs 75 straddling the upper end portion of the tube 10 and also the upper end of the rod 20, and provided in their free end portions with downwardly opening notches 23, which receive respective ends of a cross-pin 24 on the 80 rod 20. The closed end of the lever 21 projects into a side opening 25 in the head 3, and is engaged therein by an operating trigger 26, which extends downwardly from said opening without the head 3 in position to be 85 grasped and operated by the first, or first and second, fingers of a hand grasping the head. The trigger 26 is fulcrumed on a pin 27 and has a rearwardly extending finger 28 near its fulcrum, which engages under the 90 closed end of the lever 21, whereby an inward movement of the trigger 26 will actuate the lever 21 to impart a downward movement to the rod 20 and its plunger, thus forcing liquid from the pump cylinder outward to and from the nozzle 7 through the communicating passages. The rod 2 is normally held in raised position by the action of a compression spring 29 thereon, thus normally retaining the operating parts in the positions shown in Fig. 1.

The outward movement of the trigger 26 relative to the head is limited by its shouldered coaction with the head, as at 30.

This manner of connecting the trigger to the plunger rod 20 provides a simple and efficient means for communicating a rapid and forceful liquid-discharging movement to the plunger from a slight movement of the trigger, and also provides a compact assembly of parts. The relative lengths of the arms of the lever 21, as shown, enables a slight movement of the trigger to impart a considerably greater movement to the plunger. While this feature appears simple, it is quite important in practice, as it enables an operator to secure a considerable movement of the plunger by only slight movement of his fingers, thus making it possible for him to reciprocate the trigger to maintain a powerful discharging pressure of the liquid without the tiring action that would otherwise occur.

The discharge nozzle embodies a cleaning feature which enables the nozzle orifice to be easily and quickly cleaned, should it become clogged by the presence of small particles of dirt, or other matter in the liquid being sprayed. This clogging is bound to frequently occur in devices of this class, due to the small needle-like size of the discharge orifice 8.

In the present instance, the nozzle 7 is reciprocally mounted in the outer end of a nipple, or coupling member, 31, which is threaded at its inner end on the tube 6, and the outward movement of the nozzle relative to the nipple is limited by the engagement of a collar or enlargement 32 on the inner end of the former, with a coacting shoulder or stop portion 33 in the latter. A coiled contractile spring 34 is disposed within the nipple and acts on the inner end of the nozzle to normally retain it in projected relation to the nipple. A stationary cleaner stem 35 is provided coaxially in the nipple 31, with its outer end projecting into a bore 36 in the inner end of the nozzle, and provided with a needle projection 37 of substantially the cross-sectional size and shape as the discharge orifice 8, and in position to enter such orifice and clean the same of accumulated matter when the nozzle is forced inwardly relative to the nipple 31 against the tension of the spring 34. It is apparent that such cleaning of the discharge orifice may be easily and quickly effected without stopping the operation of the gun by merely pressing inward on the nozzle. The stem 35 is carried by a spider 38, the annulus of which, in the present instance, is mounted in the inner end of the nipple and held firmly against a shoulder therein by its coaction with the inner end of the tube 6 when the nipple is screwed home thereon. The pressure of the oil in the discharge tube cooperates with the spring 34 to return the nozzle 9 to its forward position.

I wish it understood that my invention is not limited to any specific construction, arrangement or form of the parts, as it is capable of numerous modifications and changes without departing from the spirit of the claims.

Having thus described my invention, what I claim as new, and desire to secure by United States Letters Patent, is:

1. In a device of the class described, a receptacle, a hollow handle member mounted on the top of the receptacle, a tube depending from the interior of the handle down into the receptacle, a pump body carried thereby and having a cylinder in inwardly opening valve-controlled communication with the interior of the receptacle and in outwardly opening valve-controlled communication with said tube, a discharge tube carried by the handle and in communication with said first tube, a plunger operating in said cylinder, a rod extending from the plunger up into the hollow of said handle, an operating lever for the rod mounted in the handle, a control trigger carried by the upper end portion of the handle in operating connection with said lever, whereby an inward movement of the trigger will impart a downward movement of the plunger, and means normally retaining the plunger in raised position.

2. In a device of the class described, a receptacle having an open neck, a hollow head member of vertically elongated form detachably mounted on said neck and forming a handle, means forming a pump cylinder and suspended from the head member into the receptacle, said means having inwardly opening valve-controlled communication with the receptacle, means forming an outwardly opening valve-controlled discharge passage from said cylinder up through a portion of said member and from the outer end thereof, a plunger in the cylinder, a stem projecting from said plunger upwardly into the head member to near the upper end thereof, a spring acting on said rod to normally retain it in raised position, a trigger fulcrumed to the upper end portion of the head member and extending downward therefrom at the outer side thereof, a lever fulcrumed within the upper end portion of the head member and connecting said trigger and rod, whereby an inward movement of the trigger will impart a downward movement to the rod.

3. In a device of the class described, a receptacle, a hollow head member detachably mounted thereon in vertically extended relation to the receptacle to form a hand-grip, a discharge nozzle carried by the outer end of the head, means forming a pump cylinder within the receptacle and having inwardly opening valve-controlled communication with the receptacle and having a tube extending upwardly into the head member in communication with said nozzle and in outward-

ly opening valve-controlled communication with said cylinder, a plunger in said cylinder, a rod extending upwardly from the plunger into the head member to near the upper end thereof, means normally moving the rod in one direction, a U-shaped lever mounted in the upper end of the head member in straddling relation to said tube and having the free ends of its legs engaged to said rod, the fulcrum of said lever being at the opposite side of said tube to said rod, and a trigger pivoted to the upper end portion of the lever with an operating part projecting without the head member and with a part projecting into said member and engaging the looped end of said lever, whereby an inward movement of the trigger will impart a rod-actuating movement to the lever in opposition to said other actuating means.

20 In testimony whereof I have hereunto signed my name to this specification.

HAROLD A. ROSELUND.
